Patented June 30, 1863
Smith & Brown's Design for Stove Plates of Cooking Stove.

Des. 1793

Garrison Smith, and Henry Brown, of Philadelphia, Penn.

Assign to

Arth, Chase and North, of Philadelphia, Penn.

Letter's Patent No. 118,1793, dated June 30, 1863.

The schedule referred to in these Letters Patent and making part of the same.

To all whom it may concern:

Be it known that we, Garrison Smith, and Henry Brown, of the firm of Smith and Brown, of the City of Philadelphia in the State of Pennsylvania, have invented or produced a new and original Design for the Plates of a Cooking Stove; and we do hereby declare that the following is a full and exact description thereof, reference being had to the accompanying drawings, making a part of this specification, in which figure 1. is the top plate, Figure 2. the ash pit plate, Figures 3. and 4. the oven doors. Figure 5. one of the two front fire doors, and Figure 6. one of the two end fire doors or grates.

The top plate (figure 1.) is bounded by a raised moulding a. a. whose transverse section is indicated by the dotted line 1.

The ash pit plate (figure 2.) is bounded by a raised moulding 2. 2. whose transverse section is indicated by the dotted line 2.

2

Dec. 1793

Each of the doors (figures 3, 4, 5, 6.) is bounded by a raised moulding c. c. whose transverse section is indicated by the dotted lines 3, and the central portion of each door is provided with a raised ornamental figure.

What we claim is a new invention or production, and desire to receive by letters patent is a Design for the plates of a Banking Store as shown and described.
